CALCULATING MACHINE

Filed Feb. 13, 1932

FIG. 1

FIG. 2

UNITED STATES PATENT OFFICE

EDWIN F. BRITTON, JR., OF MAPLEWOOD, NEW JERSEY, ASSIGNOR TO MONROE CALCULATING MACHINE COMPANY, OF ORANGE, NEW JERSEY, A CORPORATION OF DELAWARE

CALCULATING MACHINE

Application filed February 13, 1932. Serial No. 592,696.

The invention has relation to calculating machines, and more particularly to means for preventing operation of an electrically driven machine while any of the digit selecting keys are in partially set position.

4 The invention consists in the novel construction and combination of parts, as set forth in the appended claims.

In the accompanying drawing, illustrating the invention:

10 Fig. 1 is a transverse section through the keyboard of a calculating machine to which the invention has been applied.

Fig. 2 is a detail plan view of the circuit breaker.

15 In the drawing the invention is shown as applied to a calculating machine having electrically driven operating means of the type shown in Patent 1,837,785, issued December 22, 1931 to Fred Masch, and entitled Switch mechanism for calculating machines. The digit selecting mechanism illustrated is in accordance with the disclosure of Patent 1,399,652, issued December 6, 1921 to E. E. Phinney and entitled Setting up means for calculating machines. It will be obvious that the invention may be applied equally well to electric drive means and selector mechanism of widely varying types.

20 In the drawing, numeral 18 designates the digit determining keys, operable through the selector bails 19 to set up values, to be registered upon subsequent operation of the machine in the well-known manner. Any desired number of columns of keys 18 may be provided each column having a related lock bar 6, whereby any key depressed in a given column may be locked in set position.

25 As each key is depressed the related lock bar 6 will be moved laterally by cam tooth 10 of the key, this movement being transmitted to a slide 86, disposed transversely of the locking bars 6 and provided with a lug 87 engaging a lever 88 forming part of a circuit breaker interposed in the circuit of the motor

100 which drives the operating mechanism of the machine. This circuit breaker includes normally engaged contacts 89 mounted upon the ends of spring arms 90, with one of which arms insulated roller 91 contacts, this roller being carried on the free end of lever 88. A spring 92 is fast to lever 88 and serves to hold the parts yieldably in normal position.

30 It will be obvious that upon movement of any key 18 from or to set position, lever 88 will be displaced, and the contacts 89 separated, so that the motor 100 cannot be operated until the key arrives in depressed or in elevated position. Therefore, it will not be possible to start the machine before completing the setting of such keys as have been touched by the operator or before depressed keys, having been released by any well known clearing means, have returned to inactive position.

35 It may be noted that the keyboard illustrated is of the "flexible" type wherein the depression of a key automatically releases any previously depressed key in the same column, and that the present invention prevents operation of the machine until both such keys 40 reach their readjusted positions.

I claim:

45 1. In a calculating machine having settable digit determining keys and operating means including an electric motor; a circuit breaker 45 in the motor circuit having normally closed contacts, and means operable by said digit keys and acting to separate the contacts of the circuit breaker while a key is in partially set position.

50 2. In a calculating machine having settable digit determining keys and operating means including an electric motor; a circuit breaker 50 in the motor circuit having normally closed spring contacts, and a lever, displaced by the keys in moving to or from set position and operable to move one of said contacts, to break the circuit.

55 3. In a calculating machine having a plurality of columns of settable digit keys and

operating means including an electric motor;
a circuit breaker in the motor circuit having
normally closed contacts, bars each movable
by any key of a column during movement
5 thereof to or from set position, and a device,
common to said bars and movable thereby to
separate the contacts of the circuit breaker.

Signed at Orange, in the county of Essex
and State of New Jersey, this 11th day of
10 February A. D. 1932.

EDWIN F. BRITTON, JR.
